UNITED STATES PATENT OFFICE

CARL F. HAAS, OF SOUTH BEND, INDIANA, ASSIGNOR TO WESTINGHOUSE ELECTRIC
AND MANUFACTURING COMPANY, A CORPORATION OF PENNSYLVANIA

DESIGN FOR A BASE FOR LAMP STANDARDS

Application filed November 13, 1929. Serial No. 33,434. Term of patent 14 years.

To all whom it may concern:

Be it known that I, CARL F. HAAS, a citizen of the United States, residing at South Bend, in the county of St. Joseph and State of Indiana, have invented a new, original, and ornamental Design for a Base for Lamp Standards, of which the following is a specification, reference being had to the accompanying drawings, constituting a part hereof.

Fig. 2 is a front elevational view of the base shown in Figure 1.

I claim:

The ornamental design for a base for a lamp standard substantially as shown.

In testimony whereof, I have hereunto subscribed my name this 8th day of Nov., 1929.

CARL F. HAAS.
